CLAIM

We claim the ornamental design for an audio connector, as shown and described.

DESCRIPTION

FIG. 1 is a perspective view of an audio connector in accordance with an embodiment of the present design.

FIG. 2 is a top view for the audio connector in accordance with the embodiment of the present design.

FIG. 3 is a bottom view for the audio connector in accordance with the embodiment of the present design.

FIG. 4 is a left side view of the audio connector in accordance with the embodiment of the present design.

FIG. 5 is a right side view for the audio connector in accordance with the embodiment of the present design.

FIG. 6 is a front view for the audio connector in accordance with the embodiment of the present design; and,

FIG. 7 is a back view for the audio connector in accordance with the embodiment of the present design.

The broken line portions in the figures are included to show portions of the audio connector that form no part of the claimed design.
